UNITED STATES PATENT OFFICE.

GEORGE WOODALL, OF SACRAMENTO, CALIFORNIA, ASSIGNOR OF ONE-HALF TO FRANCIS J. HICKEY, OF SACRAMENTO, CALIFORNIA.

LOW-WATER ALARM.

No. 888,807.

Specification of Letters Patent. Patented March 24, 1908.

Application filed November 16, 1907. Serial No. 402,423.

To all whom it may concern:

Be it known that I, GEORGE WOODALL, citizen of the United States, residing at Sacramento, in the county of Sacramento and State of California, have invented new and useful Improvements in Low-Water Alarms, of which the following is a specification.

My invention relates to a device for indicating when water is low in steam boilers.

It consists in a combination of parts, and in details of construction which will be more fully explained by reference to the accompanying drawings, in which—the figure is a sectional elevation of the upper portion of a boiler showing the device.

As shown in the drawing, A is the boiler-shell and B is the crown-sheet of the fire-box, these being related and united in the usual manner.

The central portion of the crown sheet is raised to form a small arch as shown at B'. This arched portion being raised above the main portion of the crown-sheet will be first exposed if the water becomes low, and the remainder of the crown-sheet being still covered with water, will not be uncovered before an alarm has been given.

A plug or socket-piece 2 made of brass or other suitable metal is screwed into the top of the crown-sheet. The upper part of this socket-piece extends into the boiler-space and is counterbored. This counterbore is filled with a fusible plug 3 which will melt at a heat less than that which will injure the iron of the crown sheet.

Openings are made transversely through the socket-piece 2 connecting with the boiler-space so that the fusible plug is exposed through these openings. An opening is also made downwardly through the socket-piece 2, and this opening may either be left open, so that if the metal 3 is fused it can entirely escape clear of the socket-piece 2, or if it is preferred not to allow it to escape, then a screw-plug 4 is fitted into the lower end of this opening, in which case a sufficient space must be left above this plug to contain the soft metal after it has been melted.

From the top of the socket-piece 2 a tube 5 extends upwardly through a stuffing-box 6 in the top of the boiler-shell A, and this insures a tight joint at this point.

At a convenient point on the upwardly extending tube 5 exterior to the boiler, is fixed a tube 7 which may be disposed horizontally

or vertically as desired. To this tube is connected a whistle or other alarm device, and if desired a second pipe as at 8 may lead from the T or cross 9 to discharge steam into the fire-box to extinguish the fire therein.

The operation of the device thus far described will be as follows: If the water becomes low enough to expose the upper part of the socket-piece 2 this will become so heated as to melt the fusible alloy at 3, which dropping down below the transverse openings at 2^a will admit steam directly from the boiler, and this steam passing up the tube 5 will be discharged to the whistle or other alarm device, calling attention at once to the fact. If the opening at the bottom of the socket-piece 2 be not closed, steam or steam and water will also pass through this opening to extinguish the fire, and the same result may be accomplished or assisted by means of the pipe 8. It is however not desirable in all cases to stop the fire, or kill the engine. I have therefore shown a means for closing the opening made by the fusing of the alloy and this closing may be effected after attention has been called to the state of the water by the alarm. It consists of a stopper 10 having a shaft or rod 11 extending upwardly through the tube 5, and through a proper stuffing-box 12 above the whistle connection, and the upper end of this rod may have a hand-wheel or other device 13 by which it can be turned. A portion of the rod passing through the lower part of the stuffing-box is screw-threaded so that the rod may be advanced in either direction.

Wing-guides are shown at 14 in conjunction with the stopper 10 to insure the proper alignment thereof. The lower part of the stopper 10 carries a cone 15 of fusible metal which is so shaped as to fit into the socket in the socket-piece 2 after the fusible metal 3 has been melted out; thus it will be seen that after the alarm has been given by the melting of the fusible plug 3, the space previously occupied by said plug may be immediately filled by screwing down the stem 11, and the stopper with its fusible plug 15, the latter filling the space formerly occupied by 3, and preventing any further escape of steam. If for any reason this fusible shoe 15 should also be melted, the point of the stopper 10 is so formed that it may be screwed down into the fusible plug chamber, and the passages therefrom closed to prevent the

escape of steam. This is especially desirable in the case of locomotives or engines where it is not desired to lose steam and stop the engine, and in such cases the alarm will 5 be sufficient to call attention to the condition of the water, and steam may be kept up until the condition of the water-supply is rectified.

Having thus described my invention, what 10 I claim and desire to secure by Letters Patent is—

1. A low water alarm apparatus for steam boilers, consisting of a chambered stopper having openings transversely through its 15 sides forming an open connection with the steam space near to the danger point, a fusible plug normally closing said transverse openings, a pipe extending upwardly and having an alarm connection therewith exterior to the boiler, said pipe being in open communication with the steam space of the boiler by the melting of the fusible plug.

2. In an apparatus of the character described, a socket-piece fixed in the top of the 25 crown - sheet, a pipe extending upwardly therefrom, said pipe being fixed to the upper end of said socket piece, and a whistle or alarm connection with the upper part of the pipe, said socket piece having transverse 30 openings forming an open communication between said socket-piece and the interior of the boiler, and a fusible plug by which said openings are normally closed while the plug remains intact.

3. In an apparatus of the character described, a chambered socket-piece fixed in the upper part of the crown-sheet of a boiler, and having open communication with the interior of the boiler, a fusible plug by which 40 said opening is normally closed, and exposed by the melting of said plug, a tube extending upwardly from the socket-piece having the whistle or like alarm attachment connected with it exterior to the boiler, and a 45 manually - actuated stopper whereby the opening exposed by the melting of the plug may be again closed.

4. In an apparatus of the character described, a crown-sheet having its upper portion raised above the general level of the 50

sheet, a chambered socket-piece fixed in said raised portion, said socket-piece having openings transversely through its sides forming an open communication with the interior of the boiler-space, a fusible plug filling the 55 chamber and normally closing said side openings, an extension of the chamber below that portion occupied by the fusible plug, said extension adapted to receive the fused metal after it has passed from the chamber, 60 and a pipe connected with the socket-piece having an exterior alarm connecting therewith.

5. In an apparatus of the character described, and in combination with the boiler, 65 a fire-box crown-sheet having an elevated central portion, a chambered socket-piece fixed in said elevated portion having openings transversely through its sides forming an open communication with the interior of the boiler above the crown-sheet, a tube 70 connecting with said chamber, a stuffing-box through which said tube passes through the boiler-shell, a whistle and alarm connection with said tube, and a manually operated supplemental stopper movable to close the passage through the chambered 75 socket after the alarm has been given.

6: In an apparatus of the character described, and in combination with the boiler and crown-sheet, a chambered socket-piece fixed in the top of the crown-sheet and having open communication with the boiler steam space, a fusible plug normally closing 80 said connecting passages, connections between the socket - piece and an exterior alarm, an extension into which the fused metal may pass, a supplemental guided stopper having a fusible tip adapted to fit the chamber in the socket-piece, and a stem or 85 shank, with exterior means for advancing it to close the discharge passages of the socket-piece.

In testimony whereof I have hereunto set my hand in presence of two subscribing witnesses.

GEORGE WOODALL.
